UNITED STATES PATENT OFFICE.

ISAIAH E. HINDMAN, OF BEECHVIEW, PENNSYLVANIA, ASSIGNOR TO THE DUFF MANUFACTURING COMPANY, OF PITTSBURGH, PENNSYLVANIA, A CORPORATION OF PENNSYLVANIA.

RAIL-FASTENER.

1,089,704.

Specification of Letters Patent. Patented Mar. 10, 1914.

Application filed November 26, 1913. Serial No. 803,173.

To all whom it may concern:

Be it known that I, ISAIAH E. HINDMAN, a citizen of the United States, residing at Beechview, in the county of Allegheny and 5 State of Pennsylvania, have invented a new and useful Improvement in Rail-Fasteners, of which the following is a full, clear, and exact description, reference being had to the accompanying drawings, forming part of 10 this specification, in which—

Figure 1 is a plan view of one form of my improved fastener, shown in connection with a rail; Fig. 2 is a sectional view, on the line II—II of Fig. 1; Fig. 3 is an end view 15 of one of the fastening members shown in Figs. 1 and 2; Fig. 4 is a plan view of a modified form of fastener; and Fig. 5 is a side elevation of one of the members shown in Fig. 4.

20 This invention relates to an improvement in rail fasteners, and is designed to provide a cheap and efficient device of this character for securing rails to stringers, ties or other supporting members.

25 The precise nature of my invention will be best understood by reference to the accompanying drawings, which will now be described, it being premised, however, that various changes may be made in the details of 30 construction and arrangement of the parts without departing from the spirit and scope of my invention as defined in the appended claims.

Referring to the construction shown in 35 Figs. 1 to 3, the numeral 2 designates the fastening members, each of which is provided with a base member 3, which is adapted to rest upon the tie or stringer to which they are secured. These fastening members 40 are also provided with upwardly and inwardly extending flanges 4, which are arranged to engage the sides of the rail flanges. These flanges 4 are recessed at their central portion as indicated at 5, so that only the 45 end portions of these flanges contact with the rail flanges, as indicated at 6. These members 2 are also provided with lugs 7, which are provided with openings or recesses for the securing screws or spikes. 50 Extending transversely through each base member is an opening 8, for the reception of a clamping bolt 9. The lower longitudinal edges of the bases 3 are adapted to engage each other, as indicated at 10, while the upper 55 portions of the longitudinal edges of

these base members are formed at an angle with relation to the lower portions thereof, to permit the two members 2 to fulcrum on each other along their lower edges, so that the upper portions of the flanges 4 will be moved a greater distance than the lower portions of said flanges, in order to apply the greatest pressure to the rail flanges at the upper ends of the flanges 4.

In the drawings, I have shown the fastener applied to a T-rail of special design, although this clamp can readily be used in connection with the standard T-rails. I have also shown it applied to a curved rail, but it will be understood by those familiar with the art that a straight rail might readily be secured thereby.

In Figs. 4 and 5 I have shown a clamp similar to that previously described, but in this case each member 2 is provided with two securing projections 7. In these figures, I have also shown the contact points 6^a on one member in transverse alinement with the contact points 6^a on the other member, while in Figs. 1 to 3 the contact points on one member 2 are in staggered relation with the contact points on the other member. As the flanges 4 of the fastening members are recessed I am enabled to provide fastening members which can readily be used for both straight and curved rails, and at the same time provide positive means whereby the ends of the clamping flanges are brought into engagement with the flanges of the rail, without first machining the clamping faces in order to remove high spots or lumps which may be formed during the manufacture of the clamps.

The advantages of my invention result from the provision of a rail fastener having a plurality of members, which are arranged to rock about a fulcrum point, at the lower edges thereof, so as to move the upper edges of the securing flanges a greater distance than the other portions thereof and apply the greatest pressure to the rail flange by the upper edges of the securing flanges. Also from the provision of means for drawing the flanges of the rail downwardly against the base of the fastening members. Also from the provision of means for engaging the flanges of the rails by both ends of the clamping flanges of the fastener.

I claim:

1. A rail fastener comprising two mem-

110

bers, each of said members having rail-engaging projections near each end thereof and portions adapted to extend below the rail flanges, said members being arranged 5 to contact with each other below the plane of the rail flanges, so that the upper portions of said members can be moved toward each other a greater distance than the other portions thereof, and means to draw said members toward each other; substantially as described.

2. A rail fastener comprising two members, each of said members having rail flange-engaging projections near each end thereof and portions adapted to extend below the rail flanges, said members being arranged to swing toward each other about a fulcrum below the plane of the rail flanges, and a bolt extending through openings in 15 the portions below the rail flanges for drawing said members toward each other; substantially as described.

3. A rail fastener comprising two members, each of said members having rail-engaging projections near each end thereof and portions adapted to extend below the rail flanges, said members being arranged to contact with each other below the plane 25 of the rail flanges, so that the upper portions of said members can be moved toward each other a greater distance than the other

portions thereof, and a bolt extending through openings in the portions below the rail flanges for drawing said members toward each other; substantially as described. 35

4. A rail fastener comprising two members out of transverse alignment with each other, each of said members having a horizontally disposed base portion, and an upwardly and inwardly extending flange portion, said upwardly and inwardly extending flange portions being recessed, so that only the ends of said flange portions will engage the flanges of the rail, the engaging portions of the flange of one member being in staggered relation to the engaging portions of the flange of the other member, the lower longitudinal edges of the base portion being in engagement with each other, and forming a fulcrum about which said members are arranged to swing, and a securing bolt passing through openings in said base members for drawing the clamping flanges of the two members toward each other; substantially as described. 40 45 50 55

In testimony whereof, I have hereunto set my hand.

ISAIAH E. HINDMAN.
